UNITED STATES PATENT OFFICE.

ELIHU THOMSON, OF LYNN, MASSACHUSETTS.

ALTERNATING-CURRENT ELECTRIC MOTOR.

SPECIFICATION forming part of Letters Patent No. 363,185, dated May 17, 1887.

Application filed January 26, 1887. Serial No. 225,606. (No model.)

To all whom it may concern:

Be it known that I, ELIHU THOMSON, a citizen of the United States, and a resident of Lynn, in the county of Essex and State of Massachusetts, have invented a certain new and useful Alternating-Current Electric Motor, of which the following is a specification.

The object of this invention is to provide a means whereby motive power for industrial or other uses may be developed from alternating electric currents.

My present invention depends upon the discovery made by me that through the induction exercised by an alternating current or magnetic field upon a closed circuit of low resistance and high self-induction forming another coil or closed band and through the self-induction of the electric currents set up in the latter a repulsive action is established, resulting in a tendency of the closed circuit coil or conductor to move away from its inducing-field or to set itself at an angle to the inducing-field. This discovery forms the subject of another application for patent filed by me.

My present invention consists in a suitable combination of the devices referred to with a commutator, as will be hereinafter described, whereby, through an alternating current, a continuous movement, oscillatory or rotary, may be produced in a similar way to that which is produced in ordinary electric motors by the operation of a continuous electric current.

In the accompanying drawings, Figures 1, 2, 3, 4, 5, 6, and 7 illustrate devices embodying the principle which I utilize in carrying out my present invention. Fig. 8 is a side elevation of an electric motor embodying my present invention. Fig. 9 is an end view of the same. Fig. 10 is a side view and section of a modification, and Fig. 11 is an end view of the same. Fig. 12 is a side view and section of an improved form of motor, and Fig. 13 is a section of a modified form of field-coil. Fig. 14 is a partial section of an improved form of field-magnet, and Fig. 15 is a partial section on a line parallel to the shaft of the machine. Figs. 16, 17, 18, and 19 illustrate other modifications, which will be referred to hereinafter.

In Fig. 1, P indicates a coil of insulated wire arranged to be traversed by alternating

currents of moderate rapidity, and C is a cylinder or tube of copper or other good conducting metal encircling the coil or arranged in such inductive relation to the latter that strong induced currents will be set up in the closed circuit formed by the conductor C on the passage of the alternating currents in the coil P. I have discovered that by this arrangement a strong tendency to movement of the conductor C in an axial line, or in the direction of the arrow at the upper part of the figure, is produced, which tendency is an apparently continuous one in the same direction, and not in first one and then in the other direction, as might be expected. This action I believe is due to the self-induction of the currents induced in the coil P, which self-induction causes them to be continued beyond the point of change of intensity and polarity in the inducing-magnetic field excited by the alternations in coil P, so that each induced current overlaps onto the succeeding inducing-current, whereby repulsion is produced at and near the position of maximum current in the two coils, while whatever attraction results occurs near the zero of current in both coils or circuits C P. Either part being mounted, a tendency to movement in the direction of one or the other of the two arrows will result.

The effects are heightened by the employment of a core, as indicated at I, Fig. 2, consisting of a subdivided iron mass, such as a bundle of rods or bars of iron.

I find that the position of the coil P and conductor C may be reversed without changing the result. I find, also, that it is not necessary for one coil or conductor to encircle the other. For instance, the conductor C may be in the form of a ring presented, as shown in Fig. 3, to the coil P or to the magnetic field or mass acted upon by said coil.

It is best to make the conductor C, which is of low resistance, in a laminated form, as indicated in Fig. 4, where it is shown built up of a number of rings of copper or other good conducting material, which are suitably insulated from one another. The object of this is to confine the induced currents to circular paths whose plane is at right angles to the axis.

One of the coils or conductors may be mounted on a transverse or diametrical axis, as indicated in Fig. 5, in which case the movable

coil will be deflected to a position (indicated by the letter K) at right angles to the plane of the other.

If the two coils or conductors are exactly coincident in plane of current, they will remain at rest; but a very slight displacement will give rise to a continuance of the deflection on either side. In the present case the conductor C, of low resistance, is indicated as mounted on the axis T. The passage of alternating current in the coil P will cause a deflection, as indicated. The coil P might be the closed conductor and alternating currents be passed through the other conductor or circuit with the same effect.

In Fig. 6 a modification is indicated in which the alternating-current coil P is mounted so as to be movable. On the passage of alternating current it will be deflected to the position indicated by the letter K.

It is not necessary that the coils be concentric. Thus, for instance, as indicated in Fig. 7, the laminated subdivided ring or conductor of low resistance is mounted on a diametrical axis transverse to the axis of coil P, and core I, therefore, will, unless in a plane exactly parallel to that of coil P, be turned to the position indicated by dotted lines K, in which it is substantially at right angles to the coil P or the exciting mass of iron producing the inducing magnetic field.

The closed circuit-conductor may be of any desired material, and may, if desired, be formed from a coil of low-resistance conductor having its terminals properly connected to form the closed circuit. If required, increased self-induction of the current in the low-resistance circuit may be secured by including an iron core (indicated at C², Fig. 19,) in a coil forming a portion of said circuit.

Having described some of the devices utilized in carrying out my present invention, I will proceed to a description of some of the forms of a complete apparatus embodying the combinations hereinafter claimed.

Referring to Fig. 8, I have shown at P, in vertical cross-section, a coil of conducting-wire connected with any suitable source of alternating currents and serving as the inductor or generator of a magnetic field first of one and then of the other polarity, which shall act to set up currents in the closed-circuit conductor C. The latter consists of a coil or ring of metal of low specific resistance mounted on an axis diametrical to the coil P. The mounting of the shaft or axis for the movable member C is a matter of mechanical detail, which may be varied in many ways. The details at present in vogue with the constructors of electric motors may be readily used. The conductor C, consisting of a coil of wire or the like of a metal of low specific resistance, is connected by its terminals to the segments S S of a commutating ring, upon which bear brushes B B', electrically connected together, as indicated, by a bracket or support, B². The brushes and the commutator are so located that when the

movable conductor C is nearly parallel to the plane of the conductor P, or is passed just beyond the plane of parallelism, the circuit of the conductor or conductors C will be closed in the path of small resistance between the brushes B B', and will continue to be so closed until the conductor has been repelled nearly or quite to a position at right angles to the plane of coil P, when the short circuit is broken and the coil or conductor rotates by its acquired momentum to parallelism again with the coil P, when its short circuit is again automatically closed by the brushes.

It is evident that if the conductor C be made as a ring of copper or of copper plates, instead of wire, it should be broken at some point of its periphery and the broken ends connected to the commutator segments S S by any desired means. The connections may be effected in any of the ways well-known to constructors of electrical apparatus.

The details of construction of the commutator and other parts need not be set out further, since the device at present commonly used in electric motors will serve the purposes of the invention.

In Figs. 8 and 9 that member of the machine in which the induced currents are set up is made the rotating or movable member. It is obvious, however, that such member might be fixed, and that the part carrying the currents for setting up the inducing magnetic field might be made the movable member of the machine, the commutator being properly applied to close the electric circuit thereto while the parts are moving under their mutual repulsive influence, and to break the circuit or remove the current from said coil when the coil has passed to the position at right angles to the fixed member, and to keep it broken until the coil has moved again into the position where repulsion will produce continuance of movement. Thus, as indicated in Fig. 10, the conductor C, of low specific resistance metal, and consisting of a coil or of a series of plates, may be fixed, while the source of the alternating magnetic field, consisting of the conductor P, may be mounted on a shaft and may be connected with the source of alternating currents through a commutator of any suitable construction adapted to close the circuit of the coil P when the two conductors are substantially parallel, and to break said circuit or short-circuit the current from the same when the conductor has swung around to a right-angled position, and to keep it broken until it has passed again into condition of parallelism or proper inductive relation to the fixed conductor.

The conductor P may include a core or mass of iron, I, consisting either of plates or wires, which core may be stationary or may be mounted to revolve with the conductor P in any suitable manner. Fig. 11 shows the conductor P and its core mounted on the shaft and separated from the conductor C.

Several coils or conductors may take the

place of the single conductor just described, just as in some forms of ordinary machine employing a continuous current a series of armatures or conductors upon which the field acts ¹⁵ *seriatim* are used to avoid the dead-point. For an example of such a form of motor embodying my invention, reference may be had to Fig. 12. In this case a single exciting or inductive coil is used and a series of conductors or coils of low resistance acted upon in succession by the inducing field are used.

The armature or mass of iron I, consisting of laminæ or wires, either stationary or revolving, is here indicated as surrounded by ²⁰ three coils capable of rotation as a system. These coils are indicated at C C² C³ and are severally connected to the segments 1 1, 2 2, and 3 3 of a commutator, upon which bear the brushes B B', connected together. The obvious result of such construction, when the parts are properly adjusted, is that the coils or conductors will be successively short-circuited as they arrive in position substantially parallel with the plain of the coil P, and will be open-circuited when they arrive at a position at right angles thereto. Thus, as indicated, coil C, ²⁵ which has just passed the position of parallelism, has just again had its circuit closed, and as the system revolves under the repulsive influences set up by the rapid alternations of current in P, the next coil, C², is brought around to the same position and is brought into circuit, so that it in turn becomes the active propelling member, which brings the ³⁰ next coil into action.

Instead of a single coil P, two coils, as indicated in Fig. 13, may be employed, such coils having a gap between them for the passage of the shaft of the motor.

It is obvious that the coil P of Fig. 12 might be short-circuited to form the closed conductor, and that the brushes B B' might be connected to the source of alternating currents, so as to introduce alternations successively ⁴⁰ into the sets of coils C C² C³, which would then become the source of the exciting inductive field that would produce the induced currents of high self-induction in the coil P, the result being, as before, a mutual repulsion ⁴⁵ successively of the two members and a consequent continuous rotation.

To increase the intensity of the inductive field, the coil P, carrying the alternating currents, can be surrounded, as indicated in Fig. ⁵⁰ 14, by a subdivided mass of iron partially enveloping the same transverse to its circumferential axis and consisting of iron wires, plates, or rods, the ends of which face the space in which the armature or rotary conductor revolves, so as to form the pole-pieces M M, ⁵⁵ Figs. 14 and 15, analogous to the pole-pieces of a dynamo-machine.

Instead of the wires applied as shown in Figs. 14 and 15, a series of plates of iron of ⁶⁰ the form indicated in Fig. 16 may be piled upon one another surrounding the coil P, as indicated, and forming at their center suitable

pole-pieces for the production of the alternating magnetic field excited by the coil P, and acting upon the movable conductor, which is ⁷⁰ arranged to revolve in the space between the pole-pieces; or, if desired, the field may be produced by means of two bundles of iron wires, I I, or other assemblage of pieces of iron, one or both surrounded by the exciting-coils P, which carry the alternating currents. The ends of the cores or masses of iron I are presented to the revolving conductor in a similar manner to that indicated in Fig. 7, and serve to produce the alternating magnetic ⁸⁰ field, which shall act to induce currents first in one and then in the other direction in the revolving or movable conductors, and produce thereby the repulsion between the field-producing devices and the conductors upon which ⁸⁵ the same acts inductively.

By means of a commutator as herein described a continuous rotary movement may be produced.

What I claim as my invention is—

1. An electric motor consisting, essentially, of means for producing rapid alternations of magnetic field, a low-resistance conductor or a coil of good conducting metal in which currents of high self-induction may be induced ⁹⁵ by said alternations, and a commutator for alternately closing and breaking the circuit of one or the other member as the parts move into and out of inductive relation to one another.

2. The combination, substantially as described, of an alternating-current field-coil, a conductor or coil of metal of low specific resistance on normally short or closed circuit when in proper inductive relation to the field, ¹⁰⁵ and a commutator for breaking the circuit of said coil or of the exciting-coil for the magnetic field as the parts are moved out of proximity by the repulsive action of the induced currents in the low-resistance conductor, as ¹¹⁰ and for the purpose described.

3. The combination, substantially as described, of an alternating-current field-coil, a rotary ring or coil of metal of low specific resistance in which induced currents are set up ¹¹⁵ by the alternating magnetic field, and a commutator for completing the short circuit of the rotary ring or coil when in proper inductive position and breaking said short circuit as the conductor moves out of the field by the repulsive action established through the induced currents flowing on short circuit.

4. The combination, substantially as described, of an alternating magnetic field, a series of low-resistance coils or conductors of ¹²⁵ metal of low specific resistance mounted on a suitable shaft, and a commutator for closing the short circuit of said coils or rings as each is moved into proper position in the inductive field by the conductor or conductors that are moved out of the field through the repulsive effects due to the development of the induced currents of high self-induction.

5. In an alternating-current electric motor,

the combination of an alternating current coil,
a conductor of metal of low specific resistance
in which currents of high self-induction
are developed, a commutator for governing
5 the action of the apparatus when in motion
under the effects of repulsion between the coil
and field, as described, and a laminated or sub-
divided mass of iron enveloping the alternating
10 coil transversely to its circumferential
axis.

Signed at Lynn, in the county of Essex and
State of Massachusetts, this 21st day of Jan-
uary, A. D. 1887.

ELIHU THOMSON.
